WELL AND THE LIKE SINKING APPARATUS

Guillaume Jean Solomon, Paris, France

Application December 6, 1937, Serial No. 178,281
In Great Britain December 8, 1936

2 Claims. (Cl. 255—1)

This invention relates to that kind of machine for sinking wells, and for similar work such as earth boring, mining and so forth by extraction of earth, which has non-rotary earth penetrating means driven into the ground by fluid under pressure and is operated solely from the surface of the ground.

The object of this invention is to improve the said machine in respects which will hereinafter be described with reference to the accompanying drawing which shows constructional examples of the improvements in the said machine and wherein—

Figure 1 is a vertical section of a machine which has several pistons adapted to engage the bore wall or well casing and hold the apparatus substantially stationary while the earth penetrating means enters the ground.

Figure 2 is a cross-section of one of the said pistons.

Figure 3 shows the assemblage of the cover of the machine by means of studs provided with damping springs.

Figure 4 is a section of an earth penetrating cylinder which may replace the earth penetrating jaws in certain grounds.

The machine shown in Figure 1 comprises a movable earth penetrating means consisting of a hollow driving piston 6 which is slideable in the body 1 of the machine, said piston being closed at the upper part; at the lower part it is closed by the cover 5. A packing member 15 makes an air-tight seal between the cover and piston. Hinges 7 are secured to the cover 5 by pins, and dovetailed parts reduce the work of the pins to a minimum. Jaws 20 are secured to the hinges; slotted forked brackets 21 attached to the inner faces of the jaws permit the locking of the jaws, owing to their form. A hub 24 having a plurality of forked brackets is attached to the rod 3 of the piston 2, which is provided with a pressed leather piece 41, and situated in the interior of the cylinder 6. Piston 2 is slideable within hollow piston 6. The number of jaws, in the example shown in Fig. 1, is 4.

The piston has an opening 8 and a cock 13. The main body 1 of the machine is closed at the upper part by a cover 11. There is an internal annular shoulder in the main body 1 above the hollow piston 6, said shoulder being positioned above the maximum telescoped position of the hollow piston within the main body. A partition 31 rests on said shoulder and separates chamber 42 in main body 1 from chamber 43. Blocks 33 are positioned on the partition 31 and are secured

to the inner wall of the body 1. Horizontal cylindrical chambers 39 in the blocks 33 register with outwardly opening apertures of the same diameter in the side walls of body 1 and cylindric pistons 35 are adapted to slide in said chamber 5 and move outwardly of the machine to engage the bore or lining tube of the well to lock the apparatus in the well. A packing in an internal annular groove in the lower part of the body 1 seals between the body and the hollow piston 6 10 slideable therein. Two longitudinally spaced upper and lower inwardly opening orifices 30 and 18 are formed in body 1. The orifices are connected by a channel 9 formed in the body 1. An opening 8 extending through the wall of hollow piston 6 is adapted to communicate the interior of piston 6 with orifices 18 in body 1 when piston 6 has moved below upper orifice 30. Thus, compressed fluid from within the interior of body 1 above the piston 6 may enter the hollow piston 6. 20

Each piston 35 has a circumferential flange at the inner end thereof and a longitudinal rib 36 on the lowermost part of the outer cylindrical surface thereof. This rib slides over a port 32 extending through block 33 and partition 31 and opening into chamber 43. When the piston 35 is moved outwardly to engage the well wall or lining tube it uncovers port 32 to allow compressed air to pass therethrough. A stuffing box 34 positioned around piston 35 is secured in the opening 30 in body 1. A leather piece 37, together with the stuffing box, make the piston apparatus airtight.

Rods 40 are attached to cover 5 at their lower ends. An intermediate part of each rod has a part 10 of larger diameter. That part of rod 40 including piston 10 is slidably mounted in a cylinder 26 which is secured to body 1 by perforated lugs 25 and 27. The upper ends of rods 40 have nuts threaded thereon. The upper end of hollow piston 6 has a cock 13. The apparatus is attached to a cable by a ring 41 and at 45 is a pipe for connecting the body 1 with a tubular cable or a tank containing fluid under pressure.

The cylindric pistons 35 with the projecting parts 36 are located in the body 33 inside the machine "1". The projecting parts 36 in the closed position of the apparatus cover the parts 32. When the apparatus starts to function in the well the fluid under pressure pushes the pistons 35 outwardly until the projecting parts 36 50 uncovers the ports 32 so that the fluid passes through the ports into the chamber 43. In this position the pistons 35 hold the apparatus on the wall of the well.

The operation of the apparatus is as follows: 55

The apparatus is allowed to drop freely. Then through the aperture 45, compressed fluid is delivered to chamber 42, and drives the pistons 35 outwardly, due to the excess of pressure in the chamber 42 relatively to the chamber 39, so that the piston 35 sliding outwardly in block 33 will engage the lining tube or the walls of the well or the like in case the said tubes do not extend to any great depth.

10 Owing to the frictional engagement between the surfaces of the pistons 35 and of the lining tubes or well walls due to the pressure in chamber 42, the apparatus will resist a vertical force tending to raise it. The compressed fluid passing through the openings 32—which are left open by the pistons 35 in their strokes—enters the chamber 43 and drives the piston 6 downwardly to force the jaws 20 into the ground, the body 1 being held stationary by the pistons 35.

20 The size of the port 32 is made adjustable, by using a forked piece sliding at will upon the port.

When the bucket has been filled, that is, about the same time that the opening 30 is uncovered by the piston 6, the compressed fluid passes 25 through openings 30, 9 and 18 and inwardly through the orifice 8 of the bucket—which is now opposite 18—into the interior of the chamber 4, and it drives the piston 2 upwardly in order to draw the jaws 20 inwardly and thereby 30 grip the earth between them. By reducing the pressure, the pistons 35 sliding in the opposite direction due to the pressure in the chamber 39, will cover the ports.

A certain pressure prevails in the chamber 4 35 and this permits of maintaining the jaws in the stripping state. The apparatus is then raised, the pressure in the chamber 4 is relieved, and the extra pressure in the chamber 29, added to the weight, will force the jaws outwardly and thereby 40 release the earth gripped between them. The rods 40, sliding in lugs 25 and 27 provided on the body 1, serve to prevent separation of the piston 6 from the body 1 lugs, the extent to which the piston can descend being limited by impingement of nuts on the upper ends of the rods 40 45 against the lugs 21. In the cylinders 26, the air, or springs, permit of holding up the piston 6 in the interior of the body 1 during the descent of the apparatus, and when the jaws 20 sink into the 50 ground, the air in 26 is compressed by the rod 40 which descends at the same time as the piston 6. It is evident that without departing from the principle of the invention, one may make various modifications in the disposition of the parts 55 of the apparatus, or may use varied other constructions.

The apparatus serves also for the extraction of the lining tubes, and it will suffice to replace the jaws by a plate which bears upon the bottom of

the hole or of the concrete of the pile, thus gripping the tube internally and obliging it to rise on transference of the fluid pressure to the bottom of the hole by the said plate.

In order to dampen the shocks of the striking 5 part of the apparatus and to avoid breakage of the pins 19 which serve to connect the cover 5 to the hollow piston 6, use is made of damping springs 46 mounted between the cover 5 and the nuts on the pins 19 (see Figure 3). 10

Instead of jaws, for certain grounds it is possible to use a cylinder 51 with forked brackets 44 mounted in the brackets 7 in place of the jaws 20; the machine penetrates the ground, and the cylinder becomes filled with earth. When the 15 machine is raised, the earth remains in the latter, owing to the tapered form of the interior of the cylinder 51. The holes 48 serve for the evacuation of water from the interior of 51 as this latter sinks into the ground. The jaws may be attached 20 to a piece having a rectangular or any other polygonal form, and when closed they will have a pyramidal form. In other cases, the jaws have the form of a truncated pyramid, or a slightly different form, which permits the jamming of the 25 earth between them.

With the same machine, it is possible to sink wells having variable diameters or a well having a variable diameter. To do so it is simply necessary to change the brackets 7 and the jaws 20. 30

I claim:

1. A machine of the specified kind for sinking wells and similar work, comprising earth penetrating means, driving means operated by fluid under pressure for driving the earth penetrating 35 means into the earth, laterally slideable pistons on the machine for clamping the machine in operative position, cylinders on the machine in which the pistons slide, ports in the said cylinders for the entrance and escape of fluid under 40 pressure into and from the said cylinders, and ports in the said cylinders controlled by the said pistons for the passage of fluid under pressure through the said cylinders to said driving means for actuating the said driving means whilst the 45 said pistons clamp the machine in operative position.

2. A machine of the hereinbefore specified kind for sinking wells and for similar work, comprising a cylindrical machine body having an open 50 lower end, a fluid pressure actuated hollow driving piston in the machine body, a cover on the lower end of the hollow piston, earth penetrating means connected to the said cover, connecting bolts for connecting the said cover to the said hollow piston, and damping springs on the connecting bolts.

GUILLAUME JEAN SOLOMON.
